UNITED STATES PATENT OFFICE.

PETER E. PETERSON, OF SALINA, KANSAS.

DOOR FOR RAILWAY CARS.

Application filed July 22, 1924. Serial No. 727,479.

To all whom it may concern:

Be it known that I, PETER E. PETERSON, a citizen of the United States, residing at Salina, in the county of Saline and State of Kansas, have invented certain new and useful Improvements in Doors for Railway Cars, of which the following is a specification.

This invention relates to improvements in doors especially adapted for use in box cars.

Briefly stated, an important object of this invention is to provide a box car door consisting of a plurality of sections, the lowermost of which may be swung outwardly to permit of the discharge of the grain bearing against the same whereby the pressure on the upper sections of the door is relieved.

A further aim of the invention is to provide a sectional door for box cars which may be conveniently applied to a box car without substantially altering the construction of the car and without in any way decreasing the capacity or usefulness of the car.

A further object is to provide a door for box cars which is of highly simplified construction, durable in use, and cheap to manufacture.

Other objects and advantages will be apparent during the course of the following description.

In the accompanying drawings forming a part of this application and in which like numerals are employed to designate like parts throughout the same,

Figure 1 is a perspective of the improved door applied and in closed position;

Fig. 2 is a perspective of the door with the lower section in open position;

Fig. 3 is a horizontal sectional view taken on line 3—3 of Fig. 1;

Fig. 4 is a horizontal sectional view taken on line 4—4 of Fig. 1;

Fig. 5 is a vertical transverse sectional view through the door in its closed position;

Fig. 6 is a group perspective illustrating the means to support the door and the several sections of the door.

In the drawing, wherein for the purpose of illustration is shown a preferred embodiment of the invention, the numeral 5 designates one side wall of a box car and the numeral 6 designates an opening adapted to be closed by means of a door generally designated by the numeral 7.

The improved door consists of upper, intermediate and lower sections 8, 9 and 10,

respectively, the upper and intermediate sections being provided at their ends with straps 3 arranged in U-shaped formation to define hinge straps connected to the hinge bar 11. The hinge bar or tube 11 is mounted upon a vertical rod 12, the ends of which are extended angularly as indicated at 14 and are extended through the side of the car for connection with lock nuts 16. An eye bolt 18 receives the intermediate portion of the tube 11 and strengthens and reinforces the same and at the same time limits the downward movement of the upper section 8.

The lower section 10 of the door is hingedly connected as indicated at 20 to the lower edge of the intermediate section 9 and the lower section may be swung outwardly to an approximately horizontal position as illustrated in Fig. 2 when it is desired to discharge the grain or any part of it. After the pressure on the upper sections 8 and 9 has been relieved as a result of the upward movement of the lower section 10, the upper sections may then be swung inwardly to open position.

The lower section 10 is provided at its ends with locking wings 22, the outer ends of which are extended beyond the end of the lower section and are adapted to engage the jamb strips 26 of the door. This feature of the invention is illustrated in Fig. 4 and it will be seen by reference to this figure that when the extended ends of the wings 22 are engaged with the jamb strips 26 the outward swinging movement of the lower section is prevented. Of course, the wings 22 are hingedly connected as indicated at 28 to the end of the door and have their inner ends slightly reduced and formed with openings 30 for the reception of a fastening member 31 as illustrated in Fig. 1. More specifically, the ends of the wings 22 may be moved into overlapping relation so that the same may be securely held in their operative position by means of the locking device 31. The locking device 31 is in the nature of a loop carried by the lower section 10 and adapted to extend through the openings 30 and subsequently receive a locking pin carried by a chain 33. However, when the wings 22 are in their operative positions as illustrated in Fig. 1, the door is not prevented from moving inwardly, but the lower section is only prevented from moving outwardly.

In carrying out the invention the bottom of the door may be provided with piece of canvas or the like to prevent escape of small grain. The strip of canvas of the like will 5 contact with the floor of the car and provide a tight joint between the parts.

Also, one side wall of the car may be slightly recessed to receive the door when open and by reason of this recess the door 10 will be positioned flush with the inner wall of the car. Or if desired the door may be located outside the lining of the car in which case the edges of the door would be beveled. Suitable catches or other fastening devices 15 may be employed to hold the door in place, either open or closed.

With reference to the foregoing description taken in connection with the accompanying drawing it will be seen that a grain car door constructed in accordance with this invention may be quickly operated to discharge the grain from the car and when it is desired to load the car this may be done 20 quickly also. The improved lower section 25 and the associated elements form a convenient means whereby the pressure on the upper sections may be quickly relieved.

In carrying out the invention the jamb strips 26 may be provided on their inner 30 sides with hooks or other means to engage the terminal portions of the wings 22 to hold the same in their elevated positions.

Having thus described the invention, what is claimed is:

35 1. A grain car door comprising a pair of sections, means horizontally hinging one of the sections to the other section, and wings hingedly connected to the ends of one of the sections and extended beyond the ends of 40 that section to provide stops to limit the swinging movement of that section, the wings being provided with means whereby the same may be detachably secured in an elevated position to secure the associated section in an open position.

50 2. A grain car door comprising a section, a swinging section horizontally hinged to the first-named section, wings pivoted to the ends of the swinging section and extended beyond the same to define stops adapted to engage jamb strips, the inner portions of 55 said wings being adapted to overlap, and means to hold the inner portions of the wings in overlapped position.

55 3. A grain car door comprising a section, a swinging section horizontally hinged to the first-named section, wings pivoted to the

ends of the swinging section and extended beyond the same to define stops adapted to engage jamb strips, the inner portions of 60 said wings being adapted to overlap, means to hold the inner portions of the wings in overlapped position, and hinge means to support the first-named section for movement about a vertical axis. 65

4. A grain car door comprising a section, a swinging section horizontally hinged to the first-named section, wings pivoted to the ends of the swinging section and extended beyond the same to define stops adapted to 70 engage jamb strips, the inner portions of said wings being adapted to overlap, means to hold the inner portions of the wings in overlapped position, and hinge means to support the first-named section for movement about a vertical axis, there being means 75 to hold the wings in an elevated position whereby to hold the swinging section in its discharging position.

5. In a grain car door, the combination of 80 upper, intermediate and lower sections, said lower section being horizontally hinged to the intermediate section, wings vertically hinged to the ends of said lower section, said 85 wings being extended beyond the lower section to engage the jamb strips of the grain car door whereby to limit the outward swinging movement of the lower section, the inner portions of said wings being adapted to overlap each other and being provided with 90 openings, and a fastening device carried by the lower section and adapted to extend through said openings to lock said wings in overlapping position.

6. In a grain car door, the combination 95 of upper, intermediate and lower sections, said lower section being horizontally hinged to the intermediate section, wings vertically hinged to the ends of said lower section, said wings being extended beyond the lower section to engage the jamb strips of the grain car door whereby to limit the outward swinging movement of the lower section, the inner 100 portions of said wings being adapted to overlap each other and being provided with 105 openings, a fastening device carried by the lower section and adapted to extend through said openings to lock said wings in overlapping position, and means to support the intermediate and upper sections for movement 110 about a vertical axis.

In testimony whereof I affix my signature.

PETER E. PETERSON.
